UNITED STATES PATENT OFFICE

CAMILLE J. BOUX, OF COMPTON, CALIFORNIA

PLASTERER'S PLANE

Application filed September 4, 1928. Serial No. 303,817.

This invention relates to plasterer's tool and more especially to what is known as a "Dutch" plane.

When plasterers finish a flat mold surface it is not possible to run the contour gage fully into angles, either salient or re-entrant, and the unfinished corners are loaded with a plastic batch and a straight edge Dutch plane is then pushed endwise along the countered mold to dress down the corner batch to the proper surface, the chisel end of plane being driven sharp to the intersection of the angle.

No means has heretofore been devised whereby to plane down the ends of convex or concave mold or arch surfaces and my present invention resides in a tool having for its purpose to enable the correct finish of arched molds and faces at the corners and inner angles.

A further purpose is to provide a tool adjustable to operate on various convex or concave arch surfaces.

Another object is to provide a curved dressing plane of low cost, durable and simple construction and free of intricate mechanism, and which is of light weight and easily operable.

Other objects, advantages and features, and details of means will be made manifest in the ensuing description of the herewith illustrative conception; it being understood that modifications, variations, and adaptations, and employment of equivalents, and the transposition of parts and the utilization of appropriate materials may be resorted to within the spirit, scope and principle of the invention as it is more directly claimed hereinafter.

40 Figure 1 is a front view of a wall arch and its trim mold.

Figure 2 is a vertical section thereof.

Figure 3 is a side elevation of the present invention.

45 Figure 4 is a plan of the effective face thereof.

Figure 5 is a plan of the back or handle side of the plane.

Figure 6 is a section on line 6—6 of 50 Figure 3.

Figure 7 is a plan of the chisel blade.

Figure 8 is a side elevation of a variant form of the plane.

Figure 9 is a section on line 9—9 of 55 Figure 8.

A portion of a wall W is shown as having an arch A provided with a face mold F and inner mold beads B.

The present tool is designed to cut the curved faces sharp to the corner C and to 60 the angle N. The mold gages used to cut the molds cannot be run in the zones X—X and the present tool is designed to finish off the zones X by following the previously cut, set mold lines.

The tool includes a flexible strip 2 of desired width and length presenting a smooth face 3 for smoothing up a plastic surface. One end of the strip 2 has a fixed back piece 4 presenting a bevel face on which is adjustably secured a steel or other blade 5 having a chisel edge 6 intersecting the near end face of the strip 2.

The back piece 4 is secured only at one end as by a screw or bolt 7 to the chisel end of the plane strip 2 and is pivotally connected by a tongue and mortise joint, pivot 8 to an intermediate link 9 which in turn is similarly connected at 10 to a handle block 11 whose far end is slidably attached by a bolt or other means 12 having a set nut 13 whereby to clamp the plane strip 2 to the handle block 11 after the strip has been flexed to the concave or to convex, or to a flat plane as desired. Since one end of the back parts 4—9—11 is secured at 7 to the strip 2 the block 11 will shift when the strip is flexed and therefore the fastener 12 is slidable in a slot 14 in the strip 2, while the fastener is loose.

When the plane has been adjusted to match the surface A (longitudinally) it is then pushed endwise, as on the zone X, to dress the surface down to the near angle N. This planing is repeated on all surfaces of 95 the same curvature or arch. The plane is adjustable from the convex form for arch A to a concave form for the convex surfaces, as F.

Figures 8 and 9 show the strip 2 as in the 100

form of a strip of metal while Figures 3, 4, and 5 show it as a strip of wood preferably having its back kerfed transversely at 2^a to facilitate flexure of the plane.

5 It will be seen, in Figure 8, that when the plane is set to a flat face alinement on face 3 that the back parts recede therefrom except at the fastener parts 7 and 12, as will be the case also when the plane is set in concave 10 form. When the plane is convex the pivoted ends, at 8 and 10 bow outward and contact with the back face of the bowed strip 2, Figure 3.

In Figure 9 the fastener 12 is shown as 15 slidable in a guide-way 16 fixed on the metal strip 2.

What is claimed is:

1. A plasterer's dressing plane for finishing off angles and corners of molded surfaces and including a smooth faced member 20 of flexible character, and back means to which the member is secured and whereby it is stayed in set contour; said means including a train of back pieces to whose remote ends the ends of said member are attached and which form intermediate back stays.

2. A plasterer's dressing plane for finishing off angles and corners of molded surfaces and including a smooth faced member 25 of flexible character, and back means to which the member is secured and whereby it is stayed in set contour; said means including a train of back pieces to whose remote ends the ends of said members are attached, one end fixedly and one end slidably.

3. A plasterer's dressing plane for finishing off angles and corners of molded surfaces and including a smooth faced member 40 of flexible character, and back means to which the member is secured and whereby it is stayed in set contour; said means including a train of back pieces to whose remote ends the ends of said member are attached, one end fixedly and one end slidably, and clamp means for the sliding end of the 45 said member.
